UNITED STATES PATENT OFFICE.

AARON C. GOOSMAN, OF ROCHESTER, NEW YORK.

GARMENT PATTERN.

Application filed May 16, 1924. Serial No. 713,870.

This invention relates to improvements in garment patterns such as are made principally of cardboard or heavy papers, and has for its object to provide a simple and inexpensive pattern which may be easily manipulated and from which a pattern of larger or smaller dimensions may be readily made. Another object is to provide a pattern constructed in sections which are readily adjustable to vary the pattern so as to change the shape of the garment from normal to suit any variations in the shape of figure from the normal that may be necessary in the production of any garment.

The invention consists of the features of construction, combination and arrangement of parts herein fully described and claimed, reference being had to the accompanying drawings in which:

Figure 1 is a plan view of a drafting pattern constructed in accordance with my invention.

Figures 2 and 3 are longitudinal sections on the lines 2—2 and 3—3 of Figure 1.

Figure 4 is a plan view of the pattern sections separated.

Figure 5 is an enlarged detail view of a portion of the pattern.

Figure 6 is a plan view illustrating adjustability of the parts of the pattern sheet.

Figure 7 is a plan view of a modified form of pattern, adapted especially for use as a model pattern.

Figure 8 is a detail view of a portion thereof on an enlarged scale.

Figure 9 is a view illustrating the mode of producing a drafting pattern from the model pattern.

Referring particularly to Figs. 1 to 6 inclusive, of the drawings, A designates a pattern made of cardboard, heavy papers, or other suitable material, and which constitutes one element of a set of patterns for drafting a particular garment, such as a coat. This pattern is composed of a body section B and an end section or shoulder section C, the normal plane of division between said sections being along the transverse line B'. The pattern has a straight longitudinal

side margin a, and a straight end margin b, the side and end margins being shaped as required and having grade points c, d, e, f and g, from each of which extends radially in line or parallel therewith a longitudinal guide slot D, which is employed in lieu of the usual grade line of an ordinary pat-

tern. Each of these slots is of a suitable length to accord with a prescribed gauge scale H, extending along one of its margins, and which designates garment sizes, 60 as well as the particular size of garment for which the pattern is cut. As shown in the present instance, the scale ranges from pattern sizes 32 to 44, inclusive, and the numeral 38 of the scale, which indicates the size of the garment for which the pattern is designed, is prominently set off from the remainder of the numerals and denoted by a prominent scale line or indication h'. The purpose of these grade line 70 guide slots and scale will be hereinafter fully explained.

The pattern A may be designed, as shown in the present instance, for forming one of the portions or sections of a coat, waist or like garment, and its body portion B and end section C may be shaped to accord or define the neck and shoulder portion of the garment. As shown, the said sections B and C are centrally connected at their meeting portions by an elastic strip or band E, which is disposed substantially in the center line of the pattern, while adjacent the sides of the section B, and at like distances on opposite sides of the strip, are arranged spring clamping members I having tongues i, which clamping members are suitably secured to the garment section B and project over upon the extension B² of said section so as to slidably receive the adjacent edge of the section 80 C and clamp the same against said extension B². The elastic band E holds the two sections B and C assembled and prevents their separation, while the spring clamps and their fingers i serve to hold the section 90 C in fixed and adjusted relation with respect to the line B' of the section B, thus permitting the section C to be moved longitudinally with relation to the section B for the purpose of extending the length of the pattern within certain limits, or to permit the section C to be set at an angle relatively to the section B for the production of a pattern varying to a greater or less degree from the normal.

The side margins of the section B are provided in registry with the guide line B' with indicating notches j and scales extending in opposite directions from said notches, which scales are preferably arranged in one-eighth 110 inch divisions so as to indicate degrees of adjustment of the section C with relation to

the line B', while along the curved margin of the section C in proximity to the point e is a similar scale j' .

- In the use of the device as a model pattern of a fixed size, say for a No. 38 garment, it will be readily understood that the pattern sheet of normal size and contour may be readily made therefrom by simply marking off the grade line or contour points, connecting the same by pencil lines and then cutting out the pattern so marked. If it should be desired to make a pattern which is larger than the model pattern, say for a No. 40 size, this is accomplished by first marking or laying off the points on the pattern paper, scribing lines along the fixed margins a and b , and then outlining the curved margins in dotted lines, as shown in Figure 9, after which grade lines D' are marked upon the pattern sheet by means of the point of a pencil inserted through the grade line slots B and drawn along the scale margins, the lines being marked off at the point 40 to indicate the positions from which the grade lines and points are to be established. The model pattern is then adjusted to turn upon each grade line to bring the numeral 38 thereon into registry with the marked point portion of the grade line, which will set the pattern point associated with the particular grade line two pattern degrees or marks farther out beyond the dotted line. These points are so set or marked off upon the pattern sheet until this work is completed, when the new or extended pattern points are connected by outside lines, as indicated in Figure 9, the outside line determining the contour of the pattern margins for a pattern for a No. 40 garment, along which and the fixed margins the pattern is then cut out. In a similar manner a pattern smaller than the model pattern may be laid off, except in this instance that the indicating marks on the laid off grade lines will be placed inside instead of outside of numeral 38 to the desired degree, for a 32, 34 or 36 size pattern, or any intermediate or fractional size. By adjusting the section C out or in with reference to the guide line B', the length of the pattern may be varied from the normal as occasion may require to suit any abnormal figure, and it will also be understood that by adjusting one of the side margins of the pattern section C a greater distance from the guide line B' than its other side margin, and setting said pattern section C at an angle to the line B', as indicated and particularly in Figure 6, the slope or contour of the fixed and curved lines of the end or shoulder portion C may be varied to accord with peculiarities in the stoop or set of the back

and shoulders of the individual for whom the garment is designed. These degrees of adjustment may be determined by the scales associated with the notches j and the scale j' whereby the variation of the angle between the points D and E may be determined and laid off, as will be readily understood.

In the modified form of my invention shown in Figures 7 and 9, the construction is the same as that previously described, except that the body and end portions B² and C² are integral or fixed with relation to each other. This form of model pattern is to be employed in the production of drafting patterns which do not vary from the normal except in the nature of pattern size. It will be noted that in both structures the slots and pattern size scales are arranged in a similar manner with relation to the points of the pattern. Preferably the graduations of these scales are formed, except as regards the designating pattern number graduation, of comparatively small and narrow notches, the pattern number designating graduation being formed of a wider and deeper notch, so that all liability of confusion in laying off the grade lines will be avoided.

It will be evident that by the use of my improved model patterns, drafting patterns may be readily and conveniently made; that patterns of larger or smaller size than the two-part construction of model pattern various changes of a stock pattern may be easily and conveniently made as circumstances may require to provide a pattern to suit any particular shape of body. It will, of course, be understood that the patterns may be made and employed in the production of garments of all kinds, for men, women and children.

I claim:—

A garment pattern of the character described comprising body and end sections, said sections being provided with grade points and grade slots arranged adjacent the inner section of the marginal edges thereof, the adjacent grade points and grade slots being approximately arranged in alignment, a scale arranged parallel with each of said slots, an elastic band centrally connecting said sections at their meeting portions in a manner whereby to permit relative longitudinal and lateral movement therebetween, and fingered spring clamping members disposed upon each side of said elastic band and associated with said sections to permit said movement.

In testimony whereof I affix my signature.

AARON C. GOOSMAN.
